UNITED STATES PATENT OFFICE.

CHARLES D. RICHARD, OF WEST NEW BRIGHTON, AND GUY T. MORRIS, OF NEW YORK, N. Y., ASSIGNEES TO WESTERN ELECTRIC COMPANY, INCORPORATED, OF NEW YORK, N. Y., A CORPORATION OF NEW YORK.

COIL WITH MULTIPLE ADJUSTMENTS.

Application filed June 30, 1923. Serial No. 648,684.

This invention relates to coils with multiple adjustments.

It is an object of this invention to provide coils that are capable of a plurality of adjustments of different kinds and of different degrees.

A more specific object of this invention relates to an inductance coil capable of both fine and coarse adjustments.

10 A feature of this invention relates to means associated with an inductance coil for making both slow and rapid adjustments of a contact member.

15 An additional feature concerns a stop mechanism which allows a complete turn of an inductance coil to be made for effecting precise adjustments.

20 One concrete embodiment of this invention may comprise a threaded insulated cylinder wound with a coil of bare wire and rotatably supported upon a shaft. A gear driven contact device may be operated by a screw and may be transversely movable along the winding of the coil. For allowing 25 one complete turn of the coil a stop mechanism having a limited movement may be rotatably mounted upon the shaft and arranged to engage a projecting lug on the insulating cylinder. Adjusting knobs may also 30 be provided having indicating dials whereby various adjustments may be accurately repeated.

The nature of this invention and its other 35 features and advantages will be apparent from a consideration of the detailed description which follows in connection with the accompanying drawings.

In the drawings, Fig. 1 illustrates in detail 40 and partly in section one form of this invention. Figs. 2 and 3 show sections taken on line 2—2 of Fig. 1 which illustrate the stop mechanism. Fig. 4 shows a cross section of the contact member and insulating cylinder on line 4—4 of Fig. 1.

45 In the device shown in Fig. 1, a threaded insulating cylinder 10 carrying a helical winding 11 consisting of a plurality of turns of a bare conductor positioned in the grooves or threads constitutes a solenoidal induct-

50 ance coil. The cylinder 10 is preferably rotatably mounted on shaft 12 which is rigidly attached to a supporting post 13, for example, by means of a nut 25. The cylinder 10 and its associated winding 11 may be rotated by means of knob 14 attached to a short 55 spindle 16 which in turn is attached to the end plate 17 by a nut 38. The spindle 16 is provided with a hub 15 rotatably fitted to the end of shaft 12. The end plate 17 is fitted to the end of cylinder 10 and held 60 by means of screws. The opposite end of cylinder 10 may be closed except for an opening at its center through which the shaft 12 passes. A spring 40 and a washer 41 are positioned on the shaft 12 between the nut 65 31 and cylinder 10 in order to provide sufficient friction to prevent cylinder 10 from rotating when knob 27 is turned.

The movable traveler 18 which is threaded to shaft 19 is held in a slot formed in 70 the supporting member 21 and is consequently incapable of rotary movement. The traveler 18 carries a wiper 20 which is in contact with the bare conductor 11. The shaft 19 is rotatably mounted upon bearings 22 and 23 which may be integral with supporting member 21. A pinion 24 is attached to one end of shaft 19 and engages a gear 26 which may be rotated by means of knob 27 connected thereto by means of sleeve 80 28 mounted concentric with the spindle 16. The coil mechanism may be supported by an insulating panel 29 and post 13 attached to a base 30.

In Fig. 2 is shown a section on line 2—2 85 of Fig. 1 which illustrates the stop mechanism. The supporting member 21, which is mounted upon the shaft 12 and held in position by means of lock nut 31, has two prongs 32 and 33 projecting beneath the shaft 12. A dog 34 is rotatably supported upon shaft 12 and having an extension between the prongs 32 and 33. These prongs limit the motion of the dog to the space therebetween. The dog is so positioned that, when the cylinder 10 is rotated, the lug 35 projecting from the end of the cylinder will engage the extension of the dog 34. 90 95

In Fig. 2, the lug 35 and the dog 34 are shown in their relative positions with the cylinder rotated as far as possible in the clockwise direction. In Fig. 3, the position 5 of lug 35 and dog 34 is shown with the cylinder rotated as far as possible in a counter-clockwise direction. It is apparent from these figures that the movable dog operating 10 between stops 32 and 33 enables a complete revolution of the cylinder 10 to be made by allowing for the width of the lug 35. It is further apparent that the space required 15 between the prongs 32 and 33 to enable a complete revolution of the cylinder 10 should be equal to twice the width of the extension of dog 34 plus the width of the lug 35.

Fig. 4 shows a cross-section through the shafts 19 and 12 and cylinder 10 along the line 4—4 of Fig. 1. Traveler 18 carrying 20 wiper 20 is shown positioned in the groove between the sides of supporting member 21 and threaded to the shaft 19. The supporting member 21 prevents the rotation of the traveler 18 and its associated wiper 20 when 25 the shaft 19 is rotated.

In the operation of this coil, coarse adjustments are obtained by rotating knob 27, which thereby operates the gear and pinion 26 and 24 to rotate the shaft 19. This causes 30 a transverse movement of the traveler 18 and wiper 20 along the winding 11. By means of this adjustment, the finest variation obtainable is one full turn of the coil. To obtain finer adjustments in fractions of 35 one turn, cylinder 10 may be rotated by means of knob 14. The wiper 20 has a contact surface equal to the pitch of the winding 11, whereby as the cylinder 10 is rotated through one revolution, continuous contact will be maintained with the conductor. 40

Although the invention disclosed herein has been described and explained in connection with certain specific embodiments, it is not the intention that the new principles set 45 forth should be limited to these concrete illustrations, since they are applicable to numerous other modifications which will readily occur to persons skilled in the art.

What is claimed is:

50 1. A variable inductance comprising a grooved rotatable insulating cylinder, a helical winding on said cylinder, a yielding member associated with said winding for making electrical contact therewith, a rotatable shaft which rotates independently of 55 said cylinder, means including said shaft for causing said yielding member to move from turn to turn of said coil, and separate means including said cylinder for making 60 complete adjustment around the turn upon which said yielding member rests.

2. An electrical coil comprising a rotatable insulating cylinder, a helical winding thereon, a movable contact member electrici-

cally connected to said winding, means for 65 making continuous adjustment of the contact of said member with any turn of said coil, and a mechanism for limiting the angular revolution of said cylinder comprising 70 a lug on said cylinder and a dog capable of limited movement, adapted to engage said lug.

3. The combination with a variable inductance of a helical winding upon an insulating cylinder having a projecting lug of 75 means associated with said cylinder comprising a dog and separated stops, said dog being movable between said stops, and capable of engagement with said lug for permitting a complete revolution only of said 80 cylinder.

4. The combination with a variable coil of a rotatable cylinder having a projecting lug, a stop mechanism including a dog having limited motion and arranged to engage 85 said lug for controlling the angular motion of said cylinder within limits, a movable contact member, and a gear device operated by a knob whereby the position of said contact member relative to said coil 90 may be varied.

5. An adjustable coil comprising a circular drum rotatable upon a shaft, a member supported parallel to said shaft, a contact member movable parallel to the axis of said 95 drum in a slot formed in said member, and a yielding brush associated with said contact member and means for controlling the relative motion between said drum and contact member for making adjustment from 100 turn to turn of said coil and continuously around a plurality of said turns.

6. An inductance coil comprising a grooved insulating cylinder, a helical winding of a bare conductor on said cylinder, a 105 knob connected to said cylinder whereby the same may be rotated, a contact mechanism including a gear for making electrical connection with said winding, and a second knob, concentric with said first named knob, 110 associated with said gear for adjusting said contact member.

7. An inductance coil comprising a cylindrical drum rotatable upon a fixed shaft and provided with a winding of bare conductor, a rotatable shaft parallel to said fixed shaft, a contact member threaded to said rotatable shaft, means for driving said drum and said rotatable shaft whereby 115 double adjustment of said inductance may be obtained, and means limiting the angular motion of said drum to one complete revolution.

8. A variable inductance, comprising a rotatable solenoidal coil, a contact device in 120 electrical connection with said coil, means for rotating said coil, and means for moving said contact member said means comprising 125

concentric knobs provided with dials whereby the adjustments of said coil and said contact member may be indicated.

9. An adjustable coil, comprising a frame, a rotatable cylinder carrying a solenoidal winding, a rotatable shaft connected to a movable wiper engaging said coil, said shaft tending to cause rotation of said cylinder,

and a brake device for preventing such rotation comprising a washer adjacent to an end of said cylinder, and a spring positioned between said frame and said washer.

In witness whereof, we hereunto subscribe our names this 21 day of June, A. D. 1923.

CHARLES D. RICHARD.
GUY T. MORRIS.
